UNITED STATES PATENT OFFICE

GEORGE DALTON MYERS, OF CINCINNATI, AND SAMUEL RICHMOND, OF BATAVIA, OHIO,
ASSIGNORS TO THE EDWARDS MANUFACTURING COMPANY, OF CINCINNATI, OHIO,
A CORPORATION OF OHIO

SHANK SUPPORT

Application filed March 24, 1928. Serial No. 264,391.

This invention relates to shank metal members, and especially to shank supports of the type used in women's shoes wherein the outer sole is formed or molded to conform to the lower face of the shank support.

An object of this invention is to provide a shank support of the type referred to which facilitates the construction of shoes.

Another object is to provide a shank metal, the use of which makes possible the production of a more durable and comfortable shoe.

Another object is to provide a shank support which provides an integral portion inferiorly of the shoe at the rear of the ball of the foot to replace the heretofore used fillers and pads.

A further object is to provide a structure of this kind which eliminates certain labor operations commonly performed in shoes of the class referred to.

These and other objects are attained by the means described herein and disclosed in the accompanying drawings, in which:—

Fig. 1 is a top plan view of a shank support of the invention.

Fig. 2 is a side elevational view of the support shown in Fig. 1.

Fig. 3 is a cross sectional view taken on line 3—3 of Fig. 1.

Fig. 4 is a view similar to Fig. 3, but showing a modified construction of the support.

Fig. 5 is a fragmental top plan view of another modified form of the device of the invention.

In the manufacture of women's shoes the so-called arch supporting type of shoe requires a metal shank support which extends from the heel to the ball of the foot. These shank supports usually have the forward end developed into a spoon like formation, part of which lies flat with the sole and part of which merges with the shank or arch supporting metal. This shank metal lies between the inner and outer soles, and due to abrupt angle of the forward end, required the insertion of some material to support the inner sole in a relatively flat position.

The device of the present invention is of formed sheet metal and may have its shank

portion 8 of any desired width and cross sectional shape, this portion being subject to variation in accordance with the particular style of shoe or the demand of the shoe manufacturer. The rear end 9 is likewise subject to variation as to shape and location of tack holes 10. As shown in dotted lines in Fig. 1, and as is also noted in Figs. 2 and 3, the forward end is formed or dished to provide a flat portion 11 and angular corners 55 12 and 13 which meet a longitudinal rib or corner 14 extending along the body of the shank. These corners and ribs define the contour of the outer sole of a shoe, as indicated in dotted lines at 15 (see Fig. 2) and which may be quite sharp or rounded according to the style of the shoe in which the metal shank supports are to be used. The device as thus far described and exclusive of the features hereinafter described, represents the general type of shank metal members now in use. The insole is adapted to lie upon the opposite or upper face of the metal member and must of necessity avoid complete conformity with the depression or hollow occasioned by the dishing or forming as shown at 16 in Figs. 2 and 3. Heretofore it was necessary either to fill the depression with one or more pieces of material to support the insole, or to rely upon the stiffness of the insole material to be self sustaining. The tendency toward yielding of the insole and toward displacement of inserted members after a period of wear constitute a disadvantage which is obviated by the simple expedient structure of the invention.

The device of the invention consists, in its simplest form, as illustrated, in providing an integral dished plate 17 connected to the body of the shank support by a somewhat restricted bendable portion or neck 18 and permitting the periphery of the plate to contact the dished or formed portion of the device. As will be readily understood, the entire structure is stamped from a single sheet of metal and if desired the body may be formed as at 16 and the plate domed or formed as shown at the same operation. The connecting portion 18 comprises a restricted neck of metal which is later turned 90 95 100.

upon itself to provide the finished product. The forming operation strengthens the structure. The necessity for a filling material is therefore obviated since the face 19 of the plate supports the insole 20 of a shoe co-operating with the top face of the body 8 and with the upturned edges 21 in this function. The dome of the plate 17 may be slightly resilient.

10 The modification shown in Fig. 4 comprises the provision of a turned under plate 22 with the top portion 23 suitably formed and continuous with the body 8. This amounts in practice to a reversal of the parts 16 and 17 of the previously described embodiment.

15 In Fig. 5 there is illustrated a support wherein the connecting neck 18 extends from one side of the body 8 instead of from the end of the bottom member 11.

20 From the foregoing it will be understood that structural modifications may be had within the spirit and scope of the disclosure herein. The device and variations thereof 25 provide a desirable arch supporting shank metal and at the same time eliminate the undesirable depression heretofore encountered in devices now in use. The essential feature of the invention lies in the provision 30 of a single light weight stiffener or support which permits the inner and outer sole members of a shoe to be in abutment along the arch portion of the shoe and which bridges the depression at the front of the arch and adequately supports the insole thereover without added parts or labor. Shoes having shank supports of the invention embodied therein may be built along 35 graceful lines, with actual and apparent freedom from excessive weight and at the same time are capable of greater strength and greater comfort than heretofore attainable.

40 What is claimed is:

45 1. As a new article of manufacture a sheet metal shank support having a pair of integral superposed dished portions at one end.

50 2. As a new article of manufacture a shank support of sheet material for insertion between the insole and outer sole of a shoe and having adjacent one of its ends an integral overhanging formed portion whereby to solidly support both said sole members in spaced relation greater than the thickness 55 of the sheet material.

60 3. In a shoe structure the combination of an insole and outer sole secured together and a shank support member inserted between said soles, said support member having integral spaced superposed oppositely dished members at one end to space and support the sole members solidly.

65 4. A shoe shank support having one end formed into a covered hollow body said

body being generally double convex in shape.

5 5. A metal shank support comprising a body formed of a single thickness of metal and having at its anterior end a dished hollow portion and an integral portion covering said hollow portion.

70 6. A sheet metal shank support having its anterior end formed into a dished hollow portion for giving form to an outer sole and an integral member oppositely dished to cover the first mentioned hollow portion for solidly supporting an insole in spaced relation to said first mentioned hollow portion.

75 In testimony whereof, we have hereunto subscribed our names this 9th day of March, 1928.

80 GEORGE DALTON MYERS.
SAMUEL RICHMOND.
